UNITED STATES PATENT OFFICE.

WINFIELD S. LIVENGOOD, OF KANSAS CITY, MISSOURI, ASSIGNOR TO MISSOURI HAY PRESS COMPANY, OF MOBERLY, MISSOURI, A CORPORATION OF MISSOURI.

DIVISION-BOARD.

1,121,564.

Specification of Letters Patent. Patented Dec. 15, 1914.

Application filed February 6, 1914. Serial No. 816,938.

To all whom it may concern:

Be it known that I, WINFIELD S. LIVENGOOD, a citizen of the United States, residing at Kansas City, in the county of Jackson and State of Missouri, have invented certain new and useful Improvements in Division-Boards; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to division boards for hay presses, and has for its principal object to provide a board of this character, which is simple and economical, but strong in construction, and comprises means for facilitating the application of tie wires to the bales.

In accomplishing this object, I have provided improved details of structure, the preferred forms of which are illustrated in the accompanying drawings, wherein:—

Figure I is a perspective view of a part of a baling case equipped with division boards constructed in accordance with my invention. Fig. II is an enlarged side elevation of the board. Fig. III is a longitudinal section of one of the board slats, particularly illustrating the wire channels. Fig. IV is an enlarged detail perspective view of a part of the board, showing a wire channel and particularly the beveled mouth thereof.

Referring more in detail to the parts: 1 designates a baling case, which may be of any ordinary construction, but preferably 40 comprises a platform 2 and corner angles 3, forming a chute through which the bales of hay or other material are adapted for travel, after they have been pressed in a compression chamber. It is customary in 45 machines of this character to provide means for dividing the compressed material to form bales of desired length, and usually comprising boards, which are dropped into the case adjacent the compression chamber. 50 The board, which I claim as my invention, comprises slats 5, which are preferably three in number, and spaced to provide recesses 6 therebetween; the ends of the slats being beveled at their ends in order to provide

points that will enable the ends of the slats 55 to penetrate material in the compression chamber when the boards are installed. The slats 5 are connected by transverse rails 8 consisting of strips of corrugated metal comprising central sockets 9 that project into 60 transverse grooves 10 in the slats 5 and form outwardly opening grooves 11 through which the tie wires 12 may be projected when the bales are to be tied. The edges of the sockets 9 are turned backwardly and 65 laterally to form the flanges 13 that lie along the face of the slats when the rails are in place; the backturning of the edges of the sockets forming lips 14 that project beyond the faces of the slats and serve to protect the 70 heads 15 and nuts 16 of the bolts 17 by which the rails are attached to the slats, so that such heads and nuts may not contact with parts of the press, or with the material being baled therein.

When the division boards are set in place, the rails 8 are arranged in pairs on opposite sides of the board, so that both faces of the board are the same and the paired rails are secured in place by common bolts 17, which 80 extend through the slats and through the lips of the rails on opposite sides of the board. By arranging the rails in this manner, and sharpening both ends of the slats, it is immaterial which end of the board is projected into the case, as with this arrangement either end may serve as the top or bottom of the board.

In order to facilitate the projection of the tie wires through the rail sockets, I prefer 90 to bevel the rails at the ends of the sockets, as indicated at 18, so that when a wire is started into the socket it may strike the beveled edge and be guided into the socket channel.

In using the board with an ordinary hay press, the board is lowered into the compression chamber in the ordinary manner, and the material pressed thereagainst, so that the board and material are forced through 100 the baling case. When sufficient material has accumulated back of each board, a succeeding board is placed and tie wires passed around the bale; the ends of the wires being projected through the socket in the rails 8, 105 so that they may be passed entirely around the bales and tied. Should one of the slats in the board be broken, the pieces may be re-

moved by removing the bolts 17 and replacing the broken slat with a new one; the repair being much more economical than a similar repair with a board of the usual construction.

Having thus described my invention, what I claim as new therein, and desire to secure by Letters-Patent, is:—

1. A division board comprising a body member having a transverse groove therein, a corrugated rail comprising a central socket portion projected into the body groove, and flanges at the sides of the body portion overlying the face of said body member.

2. A division board comprising a body member having a transverse groove therein, a corrugated rail comprising a central socket portion projected into the body groove, flanges at the sides of the body portion overlying the face of said body member, and means for securing said flanges to the body member.

3. A division board comprising a body having a transverse groove therein, a rail having a socket portion seated in said groove, and lips secured to the body member and having outturned portions at the edges of the socket portion, and means projecting through the body member and flanges to secure the parts together.

4. The combination with spaced slats having alining transverse grooves, of a rail having a socket portion seated in said grooves, and having lips secured to the spaced members.

5. A division board comprising a body member having transverse grooves in its opposite faces, and a rail secured to opposite

faces of the body member and having socket portions projected into said grooves.

6. The combination with a plurality of spaced slats, each having pointed ends, of paired rails on opposite sides of and secured to said slats to unite the same in an integral structure.

7. The combination with spaced slats each having a plurality of transverse grooves, with the grooves in the separate slats in transverse alinement, and rails secured to said slats and having socket portions seated in said grooves.

8. The combination with a plurality of spaced slats of equal length and each having a plurality of transverse grooves in its opposite faces with relative grooves in the different slats arranged in transverse alinement, and paired on opposite sides of the slats, rails secured to the slats and having socket portions seated in said grooves with the edges of the sockets turned back and lying against the faces of the slats, and bolts extending through the flanges of the rails on opposite sides of the slats, substantially as set forth.

9. A division board comprising a body member having transverse grooves, and a rail secured to the body member and having a socket portion seated in said grooves with the end of the socket beveled to form a mouth, for the purpose set forth.

In testimony whereof I affix my signature in presence of two witnesses.

WINFIELD S. LIVENGOOD.
